(57) **CLAIM**

I claim the ornamental design for a handle of a stationery roll wheel, as shown and described.

DESCRIPTION

FIG. 1 is an upper perspective view of the handle of a stationery roll wheel showing my design.

FIG. 2 is a front view thereof;

FIG. 3 is a back view thereof;

FIG. 4 is a side view thereof;

FIG. 5 is an opposite side view thereof;

FIG. 6 is a top view thereof;

FIG. 7 is a bottom view thereof; and,

FIG. 8 is a second upper perspective view thereof, the roller wheel depicted by means of broken lines being shown for illustrative purposes only and forming no part of the claimed design.
